ATTORNEY

UNITED STATES PATENT OFFICE.

ROBERT W. ELTZNER, OF NEW YORK, N. Y.

PARQUET-FLOOR.

SPECIFICATION forming part of Letters Patent No. 256,306, dated April 11, 1882.

Application filed December 9, 1881. (No model.)

To all whom it may concern:

Be it known that I, ROBERT WILH. ELTZNER, of the city, county, and State of New York, have invented certain new and useful Improvements in Manufacturing Parquet-Floors, 5 of which the following is a specification.

This invention relates to an improved method of manufacturing parquet-floors from wood without the use of glue or other binding material; and the invention consists of a number of properly-selected pieces of wood of different colors and suitable length, which are united together by exterior metallic bands and transverse fastening strips or rails, so that when the pieces have been so connected they can be separated, by transversely sawing through them, into as many panels as bands have been used. The panels may be used for floors of rooms as well as for flooring of halls and pavements of passage-ways.

In the accompanying drawings, Figures 1, 2, and 3 represent side views of different blocks from which the panels for parquet-floors are obtained, the dotted lines representing the lines of sawing off the panels. Figs. 4, 5, and 6 are plan views of different panels. Figs. 7, 8, and 9 are side views of the individual panels shown in Figs. 4, 5, and 6. Figs. 10, 11, and 12 show the application of the same principle to stone.

Similar letters of reference indicate corresponding parts.

According to the design in which the parquet-floor is desired to be laid, there are formed a number of blocks of square cross-section from longitudinal pieces *a* of wood of square cross-section and of suitable length, which pieces differ in color according to the design. These longitudinal pieces of wood *a* are laid up together to form a composite log and united exteriorly by means of metallic bands *b*, which are fastened parallel to each other around the composite log formed by the pieces *a* at intervals of equal or varying width, according to the style of parquet-flooring to be produced.

Between the individual blocks or pieces *a* of the composite log are interposed in the plane of each exterior band, *b*, and of the same width therewith, transverse metallic strips *d*, which are nailed to the blocks, as shown clearly in Fig. 4. The blocks or pieces *a* may also be connected transversely with each other by means

of metallic cleats, which are driven into the adjoining edges of the blocks in such a manner that a rigid connection of the blocks within each exterior fastening band is obtained and 55 that they are firmly united without the use of glue.

Each block is divided by sawing through between the exterior bands, according to the dotted lines, Figs. 1 to 3, into as many separate panels *B* of three-fourths of an inch or more in thickness as there are exterior bands employed. These panels *B* are used for parquet-floors and may be laid either with or without open joints, as desired. In case closed joints are used they 65 are filled up afterward by suitable material. When the transverse metal strips *d* are interposed between the pieces *a* of the block *A* open joints are obtained, while in case they are let into grooves of the wood tightly-closing joints 70 are obtained, which are the more accurate the more exactly the strips have been fitted into the wood.

The thickness of the exterior bands, *b*, should be only one-half of the thickness of the transverse strips, so as to obtain throughout the 75 parquet-floor a uniform width of joint.

If desired, the parquet-floor can be made perfectly water and fire proof by impregnating the wood with proper chemicals. The panels 80 can be placed upon foundations of wood, cement, asphaltum, or other suitable material.

It is obvious that by a proper arrangement of colors a number of designs can be obtained, so that a very ornamental, durable, and cheap 85 parquet-floor is the result.

The same principle may also be applied to stone, only with this difference, that instead of exterior connecting-bands, galvanized-metal frames have to be used, to which the cross-strips 90 are rigidly secured. In this case the open joints will be preferred, so as to give a better foot-hold. The panels are cut off by a stone-sawing machine in the same manner as for wooden panels, each panel being secured to the floor 95 or set into cement or mortar, as desired. The filling of the joints is preferably accomplished by cement, the open portions of the joints being obtained by the insertion of pasteboard strips, which are removed after the remaining 100 portions of the joints have been filled with cement.

I am aware that wood tiles have been obtained by being transversely sawed off from composite logs the blocks or pieces of which have been glued together. I am also aware that parquet-flooring has been made of sections which are connected to each other by means of tongues or grooves. To these features I lay no claim, as I desire to avoid the use of glue and to make each panel or tile very strong and compact for itself by the exterior band and the lateral connection of the individual wooden pieces or blocks forming each panel.

Having thus described my invention, I claim as new and desire to secure by Letters Patent—

As a new article of manufacture, a tile or panel for parquet-flooring, composed of sections of wood or stone which are united with each other by internal lateral connecting devices and by exterior metallic bands, substantially as set forth.

In testimony that I claim the foregoing as my invention I have signed my name in presence of two subscribing witnesses.

ROBERT WILH. ELTZNER.
